CLAIM

The ornamental design for a cable connector for an electronic device, as shown and described.

DESCRIPTION

FIG. 1 is a front, left side perspective view of a cable connector for an electronic device showing our new design; FIG. 2 is a front view thereof; FIG. 3 is a back view thereof; FIG. 4 is a left side view thereof; FIG. 5 is a right side view thereof; FIG. 6 is a top view thereof; and, FIG. 7 is a bottom view thereof.

The uniform broken lines in FIGS. 1-7 are directed to environment and form no part of the claimed design. The non-uniform broken lines in FIGS. 1-7 are boundary lines that define the bounds of the claimed design at an end of the cable connector for an electronic device and form no part thereof.
